UNITED STATES PATENT OFFICE.

ARTHUR HANSEN AND LEIF GAARDER, OF SKOTSELVEN, NORWAY.

SPLINT CATCHER.

Application filed February 16, 1925, Serial No. 9,720, and in Norway February 22, 1924.

The rotating splint catchers which have generally been used at present have the drawback that the splints are exposed to comparatively heavy wear, so that parts of 5 the splints may be broken away and these particles mixed up with the pulp.

The present invention has for its object a splint catcher, by means of which the said drawback is avoided.

10 The splint catcher according to the present invention comprises a continuously operated conveyor belt, having narrow transverse slots, which are sufficiently wide to let the pulp through, but are too narrow for the 15 splints.

The pulp is conducted to the said conveyor near one end thereof, and during the passage the pulp is exposed to the action of a spray, whereby it passes through the slots 20 of the conveyor into a trough below the same.

At the end of the conveyor the splints are removed from the same and collected separately.

25 On the drawing is illustrated a form of the invention.

Fig. 1 is a side view of a splint catcher in accordance with the invention, and

30 Fig. 2 is a plan, showing part of the conveyor on a larger scale. The pulp to be purified passes from tank 1 through channel

2 on to a horizontally moving conveyor 3, the upper or carrying part of which lies immediately above a number of troughs 4, serving to receive the purified pulp. Spray- 35 ing tubes 5 are arranged above the conveyor.

A suitable form of conveyor is illustrated on Fig. 2.

On this figure the conveyor comprises two chains 6 which are interconnected by means 40 of rods 9 with circular cross section. These transverse rods 9 are so dimensioned and arranged with relation to each other that the space between them is large enough for the pulp to be passed through, but too narrow 45 for the splints.

The rods may be made integral with trunnions 8, forming the transverse links of the Gall-chain, and in such cases it may be desirable to provide the rods with sleeves 7 50 of suitable material.

We claim:

A splint catcher for purifying wood pulp and the like, comprising, an endless conveyor belt formed by a plurality of equidistant parallel rods, links interconnecting the rods at both ends, and sleeves on the rods and between the interconnecting links. 55

In testimony that we claim the foregoing as our invention, we have signed our names.

ARTHUR HANSEN.

LEIF GAARDER.
